UNITED STATES PATENT OFFICE.

CHESLEIGH GRAY, OF INDIANAPOLIS, INDIANA.

CEMENT-ROAD-MAKING MACHINE.

Application filed June 20, 1923. Serial No. 646,580.

To all whom it may concern:

Be it known that I, CHESLEIGH GRAY, a citizen of the United States, residing at Indianapolis, in the county of Marion and 5 State of Indiana, have invented a new and useful Cement-Road-Making Machine, of which the following is a specification.

My invention relates to improvements in apparatus for finishing concrete roads and 10 has for one of its objects the provision of an apparatus for smoothing the wet concrete when laid and striking the surface so as to properly form the camber of the road and to form a smooth surface.

15 For the purpose of disclosing my invention, I have illustrated one embodiment thereof in the accompanying drawings in which

Fig. 1 is a plan view;

20 Fig. 2 is a sectional view taken on the line 2—2 of Fig. 1;

Fig. 3 is a sectional view taken on the line 3—3 of Fig. 1, and

25 Fig. 4 is a fragmentary detail of a slight modification.

In the embodiment illustrated, I provide a traveling frame comprising a pair of longitudinally extending side members 1, preferably formed of channel irons, which side 30 members are connected at each end by a pair of spaced apart cross members 2 and 3. Diagonal struts 4 extend between the side members and one of the pair of cross members at each corner to give the frame rigidity. This frame is mounted on car wheels 5, one of which is placed at each corner of the frame and for supporting the bearings 6 of the wheels I secure, on the underside of 35 the side member 1, an angle iron 7 and slightly spaced apart therefrom and between the cross members 2 and 3, a second angle iron 8 in which is mounted the bearing 6 for the wheel.

The strike comprises a straight edge 9 which may be formed of a T-iron head down. At each end the strike is turned upwardly as at 10 and then turned as at 11 to form a support for the strike. Near each end there is provided upwardly and outwardly extending handles 12 secured to the strike and rising some distance above the strike. The handles are braced by means of a vertical brace 13.

This strike is adapted to move transversely 55 of the frame on a pair of transversely extending rails 14, which, at their ends are

secured to the side members 1 by means of hanger bolts 15. These rails are supported a proper distance above the ground level so that as the strike moves transversely thereon, it will engage and smooth the concrete. For giving the proper camber to the road, each of the rails 14 is curved upwardly, the curve being the same as the camber intended 60 to be imparted to the road.

65 For manipulating the strike, I provide a runway at each end of the frame, which runway comprises a suitable plank 16 mounted on brackets 17 secured between the sides of the transverse or cross members 2 70 and 3 of the frame.

In operation the frame is adapted to travel, or move longitudinally of the road, on the side channels 18 which are laid on each side of the road and between which the 75 concrete is filled. The channels provide a roadway form and also provide a track for the wheels 5. The concrete is deposited in front of the strike for a considerable length of road, after which the frame is moved up 80 until the strike is above the deposited concrete, operators grasping the handle at each end of the strike may then move the same transversely of the road, at the same time giving the same a slight longitudinal oscillation or reciprocation as it is moved to aid in working it across the face of the concrete and, due to the fact that the rails on which the strike travels are curved, the proper 85 camber will be imparted to the road.

90 Where a pavement is being laid with expansion joints which are defined by vertically set dividers which are left in place until the concrete hardens, the strike, at its middle, may be notched, as illustrated at 95 in Fig. 4, such notch being of sufficient length to provide for the longitudinal movement of the strike and to avoid passing over the divider in the concrete.

I claim as my invention:

100 1. In a road finishing apparatus, the combination with a supporting frame arranged to be moved longitudinally of the road, transversely extending guide members shaped to conform to the camber of the road mounted on said frame and a straight edge strike extending substantially longitudinally of the road during its entire operation and movable transversely of the road on said 105 guide members.

110 2. In a road finishing apparatus, the combination with a supporting frame mounted

to move longitudinally of the road, guide members supported on said frame transversely of the road and shaped to conform to the camber to be imparted to the road and a straight edge strike extending substantially longitudinally of the road during its entire operation and movable on said guideways transversely of the road and having a limited longitudinal movement on said guideways.

3. In a road finishing apparatus, the combination with a frame mounted for longitudinal movement along the road, transversely extending guideways carried thereby and shaped to conform to the camber to be imparted to the road, a straight edge strike extending substantially longitudinally of the road during its entire operation and supported and movable upon said guideways and having its striking surface at a level below said guideways.

4. In a road finishing apparatus, the combination with a frame mounted to move longitudinally of the road, guide members mounted on said frame and extending transversely of the road and shaped to conform to the camber to be imparted to the road, a straight edge strike extending substantially longitudinally of the road during its entire operation and mounted to move transversely of the road upon said guideways and oper-

ating handles extending above said strike and frame.

5. In a road finishing apparatus, the combination with a frame mounted to move longitudinally of the road, guide members mounted on said frame and extending transversely of the road and shaped to conform to the camber to be imparted to the road, a straight edge strike mounted to move transversely of the road upon said guideways and extending substantially longitudinally of the road during its entire operation, transversely extending runways on said frame and operating handles connected to said strike and projecting upwardly into a position to be grasped by an operator moving on said runways.

6. In a road strike the combination with a frame mounted to move longitudinally of the road, guideways extending transversely of said road and a strike extending longitudinally of the road during its entire operation and arranged to rest upon the said guideways and be moved transversely of the road thereupon.

In witness whereof, I CHESLEIGH GRAY have hereunto set my hand at Indianapolis, Indiana, this 5th day of June, A. D. one thousand nine hundred and twenty three.

CHESLEIGH GRAY.
